UNITED STATES PATENT OFFICE

ERLE R. SHEPPARD, OF NEW YORK, N. Y.

DESIGN FOR A POCKET MATCH-BOX.

47,741.

Specification for Design.

Patented Aug. 17, 1915.

Application filed January 27, 1912. Serial No. 673,948. Term of patent 7 years.

To all whom it may concern:

Be it known that I, ERLE R. SHEPPARD, a citizen of the United States, residing at New York, borough of Manhattan, in the county of New York and State of New York, have invented a new, original, and ornamental Design for a Pocket Match-Box, of which the following is a specification, reference being had to the accompanying drawings, forming part thereof.

Figure 1 is a front elevation, and Fig. 2 is a side elevation of a match-box showing my new design.

The design comprises a body portion 1, and a lid or cover 2, hinged at 3 to the body. As viewed from the side, the front and back

of the box taper in opposite directions from the lines 5, 5', the upper portion 6, and the lower portion 7, meeting in the line 5 to form a sharp, distinctive edge or angle. A ring 9, projects from the center of the upper edge or hinge of the box.

I claim:

The ornamental design for a pocket match-box, as shown and described.

In testimony whereof I have hereunto set my hand in presence of two subscribing witnesses.

ERLE R. SHEPPARD.

Witnesses:

JOHN KAHN,
MILDRED WAHLBERG.
